United States Patent

Des. 237,588
Patented Nov. 11, 1975

237,588

CANTEEN

Bernard C. Sharp, White Plains, N.Y., assignor to Poloron Products, Inc., New Rochelle, N.Y.

Filed Mar. 1, 1973, Ser. No. 337,200

Term of patent 7 years

Int. Cl. D9—01

U.S. Cl. D9—168

FIG.1

FIG.4

FIG.2

FIG.3

FIG. 1 is a top plan view of a canteen showing my new design;

FIG. 2 is an elevational view, the opposite side being the same in appearance as the side shown;

FIG. 3 is an elevational view looking from the right of FIG. 2, the opposite side being the same in appearance as the side shown; and

FIG. 4 is a fragmentary sectional view taken along line 4—4 of FIG. 2.

I claim:

The ornamental design for a canteen, as shown and described.
